HUMIDIFICATION APPARATUS

This invention relates to an apparatus for automatically supplying a source of water vapor for humidification purposes to an individual room or rooms during that part of the year when heating systems are normally used and to thereby increase the relative humidity levels in the rooms. The apparatus is used in conjunction with a recirculating hot water or hot steam heating system and in one embodiment shown will provide a constant supply of moisture whenever the heating system is operating.

The small home humidifiers of the prior art presented a number of problems, among them the need for continually replenishing the water supply as the water evaporated; usually from a pan or other vessel placed next to the radiator. They also presented difficulties arising from the impurities in the water and the resultant unsightly sediment remaining in the pan, or residue which tends to build up and clog pores of a spray-type humidifier and render the apparatus ineffective.

The apparatus of this invention utilizes the recirculating hot fluid of the heating system. The vaporizing fluid is obtained by tapping into the system as by removing the "bleeder" valve on the outlet conduit and replacing same with a bypass valve. The bypassed fluid is then lead from the valve, through a conduit, to a perforated tubing placed over the heat-radiating member or radiator. An absorbent or wicklike material is placed over the radiator and between the perforated tubing and the radiator, and is thus constantly wetted by the fluid emitted by the perforated tubing. The moisture in the wicklike material will be vaporized by the heat from the radiator. Thus, in a simplified manner a conventional heating system can be adapted for humidification purposes and such apparatus can easily be individually installed in any room desired and will not interfere with the normal operation of the heating system. The components of this humidifier can, in fact, be packaged for distribution in "kit" form and can be easily mounted by any householder.

An object, therefore, of this invention is to provide a humidifier with a constant supply of water for replenishing same.

Another object of this invention is to provide a humidifier of a simple construction which can be installed in most common recirculating fluid-heating systems.

A further object of this invention is to provide a humidifier which can be incorporated into and will automatically operate with the heating system.

Other objects and advantages of this invention will be apparent from the following description made with reference to the drawings, wherein:

FIG. 1 represents the humidifier connected with the hot water heating system.

FIG. 2 represents a block diagram of the humidistat-amplifier-driver circuit for controlling the bypass valve.

FIG. 3 represents a block diagram of the humidistat-amplifier-driver circuit and the interconnection with the thermostat.

FIG. 4 represents a circuit diagram for the humidification system.

In the embodiment shown in FIG. 1 the heat-radiating member or fin member 1, of the recirculating hot water heating system is supplied by inlet conduit 2, with hot water which passes through the fin member and leaves via outlet conduit 3. The outlet conduit of each of the radiating or fin members is equipped with a "bleeder" valve for normally controlling pressure in the system. When the "bleeder" valve is removed and a bypass valve 4, substituted therefore, a portion of the circulating fluid can then be diverted to the bypass conduit 5, without sacrificing the benefits and advantages of the normal operation of the "bleeder" valve. A section of perforated hose or tubing 6 is attached to the bypass conduit 5 and is placed over an evaporant such as a piece of absorbent material 7. The bypassed fluid will thus be conducted through the perforated tubing 6, and will thereby impregnate the absorbent material 7, placed below the tubing and above the radiator fins. Per-

forated conduit 6 may be made of a rubber or plastic composition hose or a metallic conduit such as copper tubing with a pattern of perforations formed by fine holes facing toward and in contact with an equal length of wicklike material, for example, 3/16-inch thick and 2-inch wide braided asbestos ribbon. It should be obvious that other wicklike materials such as cotton wadding will be equally as effective; also that the recirculating fluid may be steam instead of hot water.

The device will operate in the following manner; when the thermostat of the hot water system calls for heat the hot fluid will start circulating, as a consequence the fin member 1 will be heated and will heat the air surrounding the fin member, the warmed air will reduce the relative humidity. However, with the humidifier in operation part of the circulating fluid will be directed through the bypass conduit 5 and perforated tubing 6 and thus moisten the absorbent material 7 wherefrom it will be evaporated to increase the moisture content of the air and resultant relative humidity. Thus, it can be seen that whenever the thermostat calls for heat, the hot water then circulating will of necessity pass through the bypass valve and a portion thereof will be conducted to the absorbent material. Since the fluid is not evaporated directly from the perforated tubing there is little likelihood that impurities in the fluid will clog the pores of the perforated tubing and the absorbent material itself can be easily replaced periodically if residue accumulates therein.

In a more sophisticated embodiment a humidistat-amplifier-driver relay circuit, as shown in FIG. 2, is incorporated into the apparatus for controlling the opening and closing of an electrically operated bypass valve. Whereas in the previously disclosed system the demand for heat would always generate a supply of bypassed circulating fluid for the humidistat, in this embodiment if the relative humidity falls below a predetermined setting, a signal is sent from the humidistat 8 which is amplified by the amplifier-driver 9 to provide power for activating a solenoid 10, the latter in turn will operate the bypass valve 4. Thus the humidistat can be made to independently open or close the bypass valve in response to a predetermined setting of the humidistat and this will occur regardless of the temperature setting on the thermostat.

It should be apparent that although the humidistat will open the bypass valve no fluid will be diverted to the humidifier unless the thermostat calls for heat.

In another embodiment a completely automatic control is established, as illustrated diagrammatically in FIG. 3, by an electrical interlinkage between the humidistat 8 and the thermostats 11 of the heating system. A comfort zone may be established between a minimum setting and the humidistat calibrated such that the bypass valve will be in an "off" position when the humidistat is in a comfort zone. If the humidistat is above or below the extremes of this zone the valve can be opened or closed accordingly. For example, if the humidistat reading drops below the minimum setting on the humidistat i.e. in the case where there is a need for increasing the humidity, the solenoid 10 activates the bypass valve 4 in a manner as previously described, and the heating system is activated by a signal from the humidistat such that there will be a call for heat by bypassing the thermostat regardless of any previous thermostat settings. This will cause a circulating of the hot fluid and the delivery of same to the humidifier.

If the humidity rises above the maximum setting of the humidistat i.e. there is indicated a need to reduce the relative humidity, the solenoid will not be activated and the bypass valve will remain closed; however a signal will be sent through the thermostat regardless of the previous settings of the thermostat and calling for additional heat and for the circulation of the hot fluid thereby permitting the radiation of warm air from the radiator which will reduce the relative humidity in the room. Once the humidity drops into the comfort zone the thermostat will again take over its normal operational control of the heating system.

The circuit diagram in FIG. 4 shows a means of implementing the above control system. The humidistat 8 may have a

double-pole double-throw switch 12 which is shown in a nonoperative or "off" position as when the humidistat is in the comfort zone. The switch is held in this position by the spring 13 which can be the moisture response coil spring of the humidistat, and is calibrated so that when the index 14 is within the comfort zone the switch will not make contact with the terminals 15 and 16. If the humidistat falls below the limits of the comfort zone, the switch 12 is moved by the spring 13 and switch terminals 17 and 18 will contact corresponding terminals 15 and 16 to complete a circuit which activates the solenoid and also will complete the circuit which overrides or bypasses the thermostat setting and will call for more heat and hot fluid circulation. If the humidistat rises above the maximum limits of the comfort zone, the switch 12 is moved by the spring 13 and switch terminal 17 will contact corresponding terminal 16 to complete only the circuit which activates the heat source. The thermostat 11 can still be utilized in its normal manner and independently of the thermostat as for example by means of a bimetallic temperature-responsive strip 19 coupled to the indicator 22 and spring 20 closing switch 21. It should be noted that electrical rather than mechanical controls can be used for operating the thermostat and/or humidistat and that the indicators 12 and 14 can be used to activate an electrical circuit to perform the above-described functions.

The above-cited embodiments are intended as exemplary and while we have described the invention with specific embodiment, further modifications will be apparent to those skilled in the art.

We claim:

1. A humidification apparatus for use with a recirculating hot fluid heating system comprising a heat-radiating member, an inlet conduit for conducting fluid into the radiating member, an outlet conduit for removing fluid from the radiating member, a bypass valve located in the outlet conduit for conducting a portion of the circulating fluid out of the system, a bypass conduit connected to the valve, and absorbent material located above and adjacent the heat-radiating

member for receiving and absorbing the bypassed fluid which is then evaporated into the air by the heat-radiating member for increasing the relative humidity thereof, a perforated tube connected to said bypass conduit and located above and adjacent said absorbent material for dropping the bypassed fluid thereonto, a solenoid connected to said bypass valve for operating same, a humidistat responsive to changes of relative humidity operatively connected to said solenoid, an amplifier-driver connected between said humidistat and said solenoid being responsive to a signal from said humidistat to activate the solenoid and thereby permit flow of fluid into the bypass conduit and on to the absorbent material, a thermostat for controlling the normal operation of the heating system, and electrical means connected to said humidistat for bypassing the thermostat control so as to activate the heating system when said humidistat calls for a change of humidity levels regardless of whether said thermostat has operated.

2. The humidification apparatus according to claim 1 wherein said electrical means comprises a double pole switch having a first position and a second position, said switch being connected to the humidistat control, the humidistat operating to move the switch to the first position when there is a need to increase the relative humidity and said humidistat operating to move the switch to the first position when there is a need to decrease the relative humidity whereby when said switch is in the first position said amplifier driver will be operated to activate the said solenoid and thereby open the bypass valve and said heating system will simultaneously be activated by connection from the switch bypassing the thermostat control so that the relative humidity will automatically be increased and whereby said heating system will be activated by the connection to said switch without activating the solenoid when said switch is in the second position so as to provide for hot fluid circulation without fluid being fed to the absorbent material so as to reduce the relative humidity.

UNITED STATES PATENT OFFICE
CERTIFICATE OF CORRECTION

Patent No. 3,596,832

Dated August 3, 1971

Inventor(s) ALBERT WHETSTONE ET AL

It is certified that error appears in the above-identified patent and that said Letters Patent are hereby corrected as shown below:

Col. 2, line 49, after "minimum" insert --and maximum--;

Claim 2, line 7, "first" should be --second--;

line 8, after "humidity" insert --,--.

Signed and sealed this 19th day of September 1972.
